COMBINED CLOSURE, POURING SPOUT, AND SIFTER

John A. Foster, Rockford, Ill., assignor to J. L. Clark
Manufacturing Co., Rockford, Ill., a corporation of
Illinois

Filed Nov. 2, 1961, Ser. No. 67,404

Term of patent 14 years

(Cl. D58—26)

FIG. 6

FIG. 7

FIG. 1 is a top perspective view of a combined closure, pouring spout, and sifter, embodying my new design, wherein the rib is of substantially uniform height throughout its length.

FIG. 2 is a top perspective view taken from the opposite side thereof.

FIG. 3 is a top plan view thereof.

FIG. 4 is a sectional view taken along the line 4—4 of FIG. 3.

FIG. 5 is a sectional view taken along the line 5—5 of FIG. 3.

FIG. 6 is a top perspective view of another form of a combined closure, pouring spout, and sifter, showing my new design wherein the rib is of decreasing height on a curved line as it nears the spout.

FIG. 7 is a top perspective view of another form of a combined closure, pouring spout, and sifter, showing my new design, wherein the rib is of decreasing height and terminates at a point midway between its starting point and the spout.

This is a continuation-in-part of my copending application Serial No. D. 63,339 filed Dec. 27, 1960, now abandoned.

I claim:

The ornamental design for a combined closure, pouring spout, and sifter, substantially as shown and described.
